UNITED STATES PATENT OFFICE.

RUFUS L. ANDERSON, OF ENERGY, SOUTH CAROLINA.

MAIL-CARRYING APPARATUS.

SPECIFICATION forming part of Letters Patent No. 598,171, dated February 1, 1898.

Application filed March 17, 1897. Serial No. 627,928. (No model.)

To all whom it may concern:

Be it known that I, RUFUS L. ANDERSON, a citizen of the United States, residing at Energy, in the county of York and State of South Carolina, have invented certain new and useful Improvements in Mail-Carrying Apparatuses; and I do hereby declare the following to be a full, clear, and exact description of the invention, such as will enable others skilled 10 in the art to which it appertains to make and use the same.

This invention relates to apparatus for transmitting mail-matter, parcels or packages, and other devices from one point to another in an expeditious and efficient manner.

The invention consists of the details of construction and arrangement of the several parts, which will be more fully hereinafter described and claimed.

20 The object of the invention is to provide means for conveying mail-matter or parcels from a central point to rural districts by rapid transit and without the delay and inconvenience consequent upon the transmission of mail and other matter by ordinary vehicles and other means now commonly employed.

In the accompanying drawings, Figure 1 is a sectional elevation of an apparatus embodying the invention. Figs. 2, 3, and 4 are perspective views and an elevation, respectively, 30 in detail of the elevator, traveler, and carrying device. Fig. 5 is a detail perspective view of a buffer used in connection with the apparatus. Fig. 6 is a side elevation of one of the supporting-poles and its attachments. Fig. 7 is a detail perspective view of the wire-supporting arm adapted to be attached to the poles. Fig. 8 is a detail perspective view 35 showing the arrangement of parts of the device at an exchange or main station.

Referring to the drawings, wherein similar numerals of reference are employed to indicate corresponding parts in the several views, 40 the numeral 1 designates a track-wire of any suitable form of construction, and is secured at one end to a main or exchange station. As shown in Fig. 1, the main or sending station has erected thereat a starting apparatus consisting of a pair of upright guides 2, supported by a suitable base and having at the lower portion thereof a release-opening 3, construct-

ed by removing the flanges of the guides, for a purpose which will be presently set forth. At the upper part of the said guides 2 is a forwardly-projecting cap or head 4, having mounted therein a sheave or pulley 5 and provided with a suitable covering or sheath 6. The said cap or head is so positioned on the guide as to permit a part of the latter to 55 project upwardly to accommodate the proper operation of the mechanism coacting therewith and has in its front end a slot 7, with a guide 8 projecting thereinto and consisting of a metallic plate with an inner angular bend 9, so arranged as to form a space with the adjacent wall of the slot 7, and at its inner portion is constructed with an overturned lip 10, to which the end of the wire 1 is secured. The said wire 1 after its securement 60 by the lip 10 passes along against and parallel with the angularly-bent end of the said plate, so that the device which moves thereover will contact with the said angularly-bent end of the plate.

The form of uprights just described will be used at small stations or substations, while the construction and arrangement shown in Fig. 8 will be employed at exchange or main stations and wherein a series of the said uprights are arranged contiguously and to receive wires from different stations.

In the construction shown in Fig. 8 the parts are all arranged similarly to those described in connection with the single pair of uprights shown by Fig. 1, with the exception that the heads extend across each other preferably at a right angle, and, as shown in dotted lines in Fig. 1, the said heads may be hooded by applying a covering thereover to protect 80 the working parts. Adjacent to the said cap or head in connection with a portion of the uprights is an engaging arm 11, which is adapted to release mechanism in a manner that will be hereinafter set forth. Movably 85 mounted in the uprights and engaging guide-grooves 12 therein is an elevator 13, consisting, preferably, of a rectangular frame having guide-flanges on opposite sides thereof to engage the said grooves 12 and also formed 90 with or having attached thereto an outwardly-projected seat 14, with spring-clamps 15, of suitable dimension, attached to opposite sides thereof. In the said seat 14 is also mov-

ably mounted an impelling-rod 16, which is spring-actuated and has an enlarged head extending beyond the front of the seat. The rear end of the said impelling-rod is pivotally connected to the lower end of a trip-arm 17, movably attached to a slotted pivotal block 18 and having its upper end recessed, as at 19, the latter being adapted for engagement with the rear hooked end 20 of an angularly-formed trip-latch 21, having an upwardly-projecting end 22 on the opposite side of the elevator-frame for engagement with the arm 11.

When the upwardly-projecting angularly-bent end of the trip-latch contacts with the arm 11, the impelling-rod is liberated to deliver a propulsive force against the device, which will be presently described. It will be understood that the said impelling-rod will be drawn back when the trip-arm is engaged by the trip-latch and that the release of the latch from the upper end of the said trip-arm will free the impelling-rod to be actuated by its spring connection.

Immediately above the seat 14 is a hanger-arm 23, with an outer reduced end 24, projecting beyond the engaging head of the impelling-rod and standing a little above the top surface of the said seat. To the upper end of the elevator is secured a suitable attaching-loop 25, to which a rope, cable, or chain 26 is secured and passes upwardly over the sheave in the cap or head, as heretofore set forth, the free end depending, for convenient engagement, from below at the base of the uprights. By this means the elevator can be moved upwardly between the uprights and will lower by its own weight. When the elevator reaches the lower portion of the apparatus, it can be removed through the releasing-opening and the rope, cable, or chain disconnected therefrom. By this means a single elevator can be used in connection with a series of upright guides, all of the latter being provided with similar releasing-openings. Of course the releasing-openings permit the elevator to be readily positioned in connection with the upright guides for proper operation.

A traveler is engaged by the elevator and consists of a main bar 27 with recesses 28 on opposite sides of the opposite ends thereof, thereby making the device as an entirely reversible, and to the said bar 27 upwardly-projecting arms 29 are attached and spaced 55 apart, the said arms being bent across the top of the bar in such manner as to project upwardly therefrom in a plane parallel with the further side and have their upper ends formed with return-bends 30, embracing and 60 providing a bearing for grooved wheels 31, adapted to have applied thereto a non-conducting covering or of themselves constructed of non-conducting material of such a nature as to resist the passage of electricity there-through. The free ends of the return-bends 30 of the said arms project sufficiently below the lower terminations of the grooved wheels

to prevent the latter from becoming readily disengaged from the track or wire over which they move, and on the outer side the said 70 arms are braced by a cross-strip 32 to thereby hold the same in proper relation to each other. The opposite ends of the arms 29 extend below the central portion of the under side of the bar 27 and are formed into loops 33, for a 75 purpose which will be presently described.

In connecting the traveler to the elevator, heretofore described, the clamps 15 embrace one end of the bar 27, fitting in the recesses 28, while the supporting-arm 23 has the wheels 80 31 mounted thereon. In this arrangement the end of the bar 27 abuts against the projecting head of the impelling-rod 16, which of course has been retracted and is held set by the trip-latch in the manner previously set 85 forth. The carrier 34 is removably attached to the loops 33 by a screw-rod 35 or other analogous device, and the rope, cable, or chain attached to the elevator is then operated to raise the latter, together with the traveler and carrier depending therefrom, to the upper part of the upright guides and under the cap or head. The several parts are so arranged in connection with the cap or head and the adjacent portion of the upright guides 90 that when the upwardly-projecting end of the trip-latch 21 strikes the engaging arm in connection with the upright guides the wheels 31 of the traveler will be in direct alinement with the wire 1 through the medium of the 100 reduced end 24 of the supporting-arm 23 passing under the lip of the guide-plate 7 to form a continuity with the said guide-plate and the wire supported thereby. At the same time the impelling-rod 16 is released to deliver its 105 full force against the traveler and start the same upon the wire 1.

The carrier 34 is intended to convey mail-matter or may be used for any other purpose desired, and in lieu thereof a well-known 110 form of parcel-carrier may be substituted. The said carrier in its preferred form is entirely closed with the exception of an opening 36 at one side, having an interiorly-arranged sliding door 37, provided with a hasp 115 at one end to engage a staple and be securely locked.

On one side of the carrier a clock-dial 38 is exposed, by means of which the time of starting or arrival of the carrier may be readily 120 determined, and at opposite ends the said carrier is formed with spring-buffers 39. The said carrier is contracted toward its opposite ends in regular curved lines and is enlarged at the center, being bulged in cross-section 125 to form a receiving-compartment of considerable size, and the material employed in the construction thereof will be of light weight, preferably aluminium; but it will be understood that any variation may be made in this 130 respect as found desirable.

The poles 40 used in supporting the wire 1 intermediate of the stations or relays are preferably formed of metal and have enlarged

bases 41, which rest in the ground. This affords an easy arrangement of the poles, and they can be further embedded in the ground at their lower ends if it is found necessary. 5 The broad bases 41 prevent the poles from sinking, and the latter are supported by guy cables or wires 42, fastened at their lower ends to suitable devices and at their upper ends attached to a suitable clamping-cuff 43. 10 Removably and adjustably mounted on the upper ends of the poles are clamping-collars 44, one of which is shown in Figs. 6 and 7, and each of which has projecting therefrom a metallic arm 45, which, as shown, is preferably given a half-turn and is secured to an interposed insulator 46, the said arm 45 being integral with one side of the clamping-collar 44. To the opposite side of the insulator 46 an angularly-bent support 47 is secured, having a part thereof standing upwardly in a vertical plane and embracing the wire 1.

The collar 44 through its adjustable arrangement permits a change in the level of the wire, as may be found desirable, to have the said wire run in the proper plane for the accurate operation of the traveler which moves thereover.

At each station, exchange, relay, or other place where the wire 1 may enter and where the removal of the traveler and detachment of the elevator is had a buffer 48 is located and consists of a rectangular frame 49 with a rear seat 50, and in the open portion of the said frame 49 is a disk or flat head 51, having a rearwardly-projecting stem or shank 52, freely movable through an opening in the seat 50, encircled by a coiled spring 53, which tends to normally throw the said disk or head 51 outwardly and also cushions the same. The said disk or head 51 is suspended within the frame 49 by suitable diagonally-arranged springs 54. These springs act as auxiliaries in cushioning the said head or disk and at the same time hold it in a central position for engagement. When the traveler and its carrier enter a station or other place, the buffer 39 on the outer end of the carrier will strike the head or disk 51 and by an easy action 50 stops the traveler without injury to the parts, it being seen that the buffers 39 project a considerable distance beyond the opposite sides of the traveler and receive the force of the blow. The rear projecting end of the stem or shank 52 when this operation ensues is adapted to strike a gong or suitable trip mechanism or contacting device to operate a signal at a distance and notify the keeper of the station, relay, or exchange that a traveler 60 with a carrier has arrived.

Whenever the wire 1 extends inward to a receiving station, relay, or exchange, it projects downwardly at an incline, as shown in Fig. 1, and through the lower portion of the upright guides, if desired, or stops outside of said guides. In either event the buffer heretofore set forth will be applied in proper en-

gaging position, and the wire or wires running into the lower end of the guide will be attached to a suitable post or other device. 70 Where a number of the upright guides are employed in connection with an exchange-station, the wires will be increased correspondingly in number both above and below—that is, one set of upright guides will be employed 75 for sending on one side and another set on the opposite side for receiving—and also the wire 1 will be arranged in connection with the upper part of the uprights or guides to extend in either direction therefrom, and the elevator in this arrangement can be reversed for operation with the wire extending in either direction. At a relay or intermediate station where one pair of upright guides are employed alone the receiving-wire will run in at the 80 bottom of said guides and the sending-wire extend outwardly from the top, so that when a carrier arrives over the bottom wire a keeper or operator will, through the medium of an elevator similar to that heretofore described, 85 again elevate the traveler, with its carrier, and send it on over the upper wire. At a terminating station the wires will be similarly arranged for both receiving and sending.

The wire 1 through the insulated features 90 heretofore set forth is adapted for use in transmitting or receiving telegraphic or telephonic messages, and by a slight rearrangement wires which have been suspended for this purpose can be readily used for engagement with the traveler and the other mechanism. It will also be understood that telephonic or telegraphic connection can be made at suitable points by station-keepers, as at the exchanges or intermediate relays in rural districts, 100 whereby a ready communication can be had with any point along the line in reference to any carrier or mail-matter transmitted thereby, the said carriers for this purpose being supplied with suitable numbers or designations, so that a proper record or registration 105 may be kept at points desirable. It will also be understood that mail-pouches of ordinary form may be placed within the carrier 34, supplied with destination-tags, and when the carrier arrives at the different intermediate stations or relays the pouch belonging to any one of said stations can be removed by the proper person and the carrier then sent onward to its further destinations.

The improved apparatus heretofore set forth will replace the ordinary star-route methods of conveying mail in rural districts, as well as stage-coaches and other vehicles, with evident advantages. It is also intended 125 to be used in large buildings requiring transferring apparatus or between two buildings, and in this use the carrier heretofore set forth may be replaced by well-known devices of a similar character or a platform, so long as it preserves the features of disconnection and ready attachment to the traveler. It will also be understood that at intermediate stations and to accommodate inequalities in

the surface of the ground suitable platforms or analogous devices may be erected where-on and from which to receive and send the traveler with its carrier. Many other advantages will appear from time to time to those using the apparatus, and changes within the scope of the invention may be made in the several parts without in the least departing from the nature or spirit of the invention.

10 Having thus described the invention, what is claimed as new is—

1. In an apparatus of the character set forth, the combination of a pair of upright guides provided with grooves therein and having a releasing-opening at the bottom formed by cutting the lower portions of the uprights away, an elevator consisting of a frame provided with flanges to engage said grooves in the guides, a traveler separably supporting a carrier and adapted to be raised by said elevator, a wire extending from the upper portion of the guides, a second wire entering the lower portion thereof at the point where the releasing-opening is formed and a spring-buffer having a stem adapted to actuate a signal, substantially as described.

2. In an apparatus of the character set forth, the combination with upright guides, an elevator removably mounted in said guides, a traveler and carrier adapted to be supported by said elevator, a wire connected to said guides, and a buffer in line with said wire having a movable stem adapted to actuate a signal, substantially as described.

3. In a device of the character set forth, the combination of upright guides, a wire attached to the upper portion thereof, an elevator movably mounted in said guides and comprising an impelling-rod, trip mechanism and a supporting-arm, a traveler having wheels adapted to rest on the said arm of the elevator and provided with a projection also engaged by a portion of the elevator, a carrier detachably connected to the said traveler, and a wire extended into the lower portion of the guides, substantially as described.

4. In an apparatus of the character set forth, the combination of a wire having a declination at a suitable point, upright guides at the point of declination, an elevating device in removable connection with said upright guides, a traveler and carrier adapted to engage the said wire and elevating device, and a buffering device adjacent to said guides having a movable stem adapted to actuate a signal, said wire being deflected from the upper part of said guides, substantially as, and for the purposes specified.

5. In a device of the character set forth, the combination of upright guides having a releasing-opening at the lower portions thereof, an elevator in removable connection with said guides comprising an impelling-rod, trip mechanism and a supporting-arm, a cap at the upper portion of the guides having an opening therein with a guide-plate, a wire attached to a part of said guide-plate, a projection to

operate the said tripping device when the elevator is raised, a traveler supporting a carrier adapted to be raised and impelled by the mechanism of said elevator, and a wire attached to the said guide-plate, substantially as, and for the purposes specified.

6. In an apparatus of the character set forth, the combination of upright guides having caps or heads thereon with an opening at one side or end, a guide-plate extending into said opening and having a lip, a wire attached to the said lip, an elevator movably mounted in said guides and comprising an impelling-rod, trip mechanism and an arm with a reduced end, a traveler supported by said arm and having a carrier depending therefrom and means for releasing the trip mechanism, the reduced end of the said arm engaging the lip to place the traveler in line with the wire, substantially as, and for the purposes specified.

7. In an apparatus of the character set forth, the combination of guides, an elevator movably mounted therein and having an arm projecting therefrom with a reduced end, a support in connection with the guides provided with a guide-plate having a lip thereon, a wire attached to said lip, and a traveler adapted to engage the arm of the elevator, and having depending therefrom a suitable carrier, said reduced end of the arm engaging the lip to place the traveler in proper alignment with the wire, substantially as, and for the purposes specified.

8. In an apparatus of the character set forth, the combination of a wire, a support therefor, a guide-plate having a lip to which said wire is attached, an elevating device with a projecting arm having a reduced end, and a traveler supporting a carrier and adapted to engage said arm, the said reduced end of the arm of the elevator engaging the lip to align the traveler with the wire, substantially as, and for the purposes specified.

9. In a device of the character set forth, a carrier having opposite tapered ends and a central bulged portion, spring-buffers located in the said tapered ends, an interiorly-arranged sliding door in one side of the bulged portion, and an exposed clock-dial on a part of said bulged portion, substantially as described.

10. In an apparatus of the character set forth, the combination with a wire, of a pole, a clamping-collar mounted on said pole and having an arm extending therefrom, an insulator attached to the outer end of said arm, and an angular support for the said wire secured to the opposite side of said insulator, substantially as, and for the purposes specified.

11. In an apparatus of the character set forth, the combination of a series of upright guides arranged at angles to each other and contiguously and having upper connecting-caps, and also releasing-openings, by cutting away the inner lower portions of each pair of guides, an elevator adapted to removably en-

gage said guides, wires entering the upper and lower portions of said guides, and a traveler adapted to engage the elevator, and having a carrier separably depending therefrom, substantially as, and for the purposes specified.

12. In an apparatus of the character set forth, the combination with the operating mechanism, of a buffer consisting of a frame, to a movable disk or head having a stem engaged

by a spring, and a series of springs attached to said disk or head and the adjacent portions of the frame, substantially as described.

In testimony whereof I have signed this specification in the presence of two subscribing witnesses.
